CLAIM

We claim the ornamental design for a motorcycle top cover, as shown and described.

DESCRIPTION

FIG. 1 is a top front right perspective view of a motorcycle top cover;

FIG. 2 is a top rear left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom view thereof; and,

FIG. 9 is a left side elevation view of the motorcycle top cover on a motorcycle.

The broken line in FIGS. 1-7 are for the purpose of illustrating portions of the motorcycle top cover that form no part of the claimed design. The broken line in FIG. 8 defines the bounds of the claimed design and forms no part thereof. The broken lines in FIG. 9 are for the purpose of illustrating the environment of the motorcycle top cover and form no part of the claimed design.

1 Claim, 7 Drawing Sheets
